UNITED STATES PATENT OFFICE

2,389,410

FOUNDATION GARMENT

Abe Meyer Butow, New York, N. Y., assignor to
Artistic Foundations, Inc., New York, N. Y., a
corporation of New York

Application May 14, 1942, Serial No. 442,980

2 Claims. (Cl. 2-38)

This invention relates to releasable closures used in tight fitting foundation garments, etc., wherein the closure means, such as that of the "zipper" type, is placed under tension in use, and which causes the "zipper" to operate with difficulty and even to break.

In my former invention for releasable closure for a garment opening, Patent No. 2,083,047, I have disclosed auxiliary hook and eye fastening means operatively secured to the "zipper" tape. The hook and eye fasteners were secured by stitching. I have found in practice that when the hook and eye fasteners are attached by stitching, that the continued pulls and strains which the fasteners are subjected to causes them to become loose and misaligned. It is a serious drawback when the user has to realign the fasteners when securing the garment edges together. It is essential to have the co-acting fastening elements match exactly even after prolonged usage.

To obviate this misalignment, I employ in the present invention garment fastening means comprising non-stretchable "zipper" tapes made of strong textile material and wherein each hook and eye fastening member is clamped directly by two rivets to the fabric strips, the two rivets being spaced apart and causing the said fastener elements to be non-yieldably held in linear alignment with said "zipper" tape. With this fastening arrangement, two spaced-apart rivets positively maintain the predetermined position of each hook and eye element and resulting in easy sliding operation of the "zipper."

In my former garment, the hooks were secured to a strip of folded textile fabric and the folds secured together in a manner as to provide a tape. The tape, which was of four-ply thickness, carried the hooks. These four plies are undesirable on account of the degree of stiffness and bulkiness which is imparted to the garment. This bulky tape actually injures the user.

In the present invention, the hooks are secured by narrow strips of metal having tubular projections or hollow rivets in spaced relation to each other and which extend through the strip of fabric and through the respective hooks. The ends of the rivets are clinched so as to permanently secure the hooks to the garment. The hooks are solidly mounted on the fabric and are fully exposed. The hooks are attached directly to the single thickness "zipper" tape and I have thereby eliminated four plies of superposed fabric at the garment opening.

In garment making practice, where the hook

end portion of each hook is not secured to the hook carrying tape, the hook end portion is loose and readily raised away from the tape into such position as to make it very difficult to hook and unhook the fasteners and the associated garment sections. In the present disclosure, the hook end portion of each hook is stitched to the "zipper" tape and these stitches retain and prevent the ends of the hooks from being raised away from the tape. Each hook is thus fixed at three points on the "zipper" tape and is immovable from its set position.

In my prior garment I utilized hook and eye tapes for reinforcing the slide-fastener tapes and for this purpose I have built up the said hook and eye tapes of a large number of layers of superposed fabric strips to provide sufficient strength. In the present disclosure I employ slide fastener tapes which are substantially non-stretchable and there is no necessity for reinforcing said slide-fastener tapes. There is accordingly no necessity for connecting the bottom portions of the slide-fastener tapes to the eye carrying shield strip with reinforcing stitching.

It is also to be noted that while I have shown in my prior garment horizontally positioned reinforcing stitching at the lower end of the opening 11 which passed through both slide-fastener tapes, that I have in the present disclosure provided a line of reinforcing stitching 29 which does not pass through both slide-fastener tapes but passes through but one of the slide-fastener tapes and solely through the eye carrying shield strip at the opposite side of the slide-fastener.

This disposition of the reinforcing stitching makes the entire length of the slide-fastener elements on the eye fastener side independent of the hook carrying shield strip, and permits the slide-fastener tape on the eye fastener side to accommodate itself to the contour of the slide-fastener tape on the hook carrying side all along its length and without being hampered by the said eye-bearing shield strip.

Among the objects of this invention is to provide in a garment closure an improved arrangement of duplex disengageable fasteners arranged to supplement each other and each to take part of the strain, one set of fasteners consisting of a slide-fastener having non-stretchable tapes and the other set of fasteners consisting of hooks and eyes, each of the hooks being directly and positively secured at three points to one of the tapes of the slide-fastener, and the eyes being positively secured to a side portion of the body of the garment at the opening.

Another object of this invention is to provide a releasable garment closure which requires a minimum of layers of material at the lower end of the closure so as to prevent injury to the wearer of the garment.

This application is a continuation in part of my application for patent for Foundation garment, Serial No. 306,361, filed November 27, 1939.

With the above and other objects in view, the invention will be hereinafter more particularly described, and the combination and arrangement of parts will be shown in the accompanying drawings and pointed out in the claims which form part of this specification.

Reference will now be had to the drawings, wherein like numerals of reference designate corresponding parts throughout the several views, in which:

Figure 1 is a front elevation of a foundation garment closure embodying my invention, the garment being shown fragmentarily.

Figure 2 is a rear elevational view of the closure looking at the inside of the garment.

Figure 3 is an enlarged fragmentary sectional view, the section being taken as on line 3-3 in Figure 1, looking only through the right hand side.

Figure 4 is an enlarged fragmentary sectional view, the section being taken as on line 4-4 in Figure 1.

Figure 5 is a fragmentary plan view of an eye bearing tape and covering shield.

Figure 6 is a fragmentary plan view of a slide-fastener tape having hooks secured thereto by riveted plates and by stitching.

Figure 7 is a fragmentary plan view of a slide-fastener tape having eyes secured thereto by riveted plates.

Figure 8 is a fragmentary cross-sectional view of the closure portion of the garment on an enlarged scale, showing the two sets of fastening devices in assembled relation along a curved surface, as it appears on the body of the wearer, the section being taken as on line 8-8 in Figure 1.

In the illustrated embodiment of the invention, the numeral 10 indicates a foundation garment having an opening 11 which is adapted to be releasably closed by a duplex set of fasteners.

One set of fasteners consists of a slide-fastener 12 and the other set of fasteners is of the hook and eye type 13. The slide-fastener 12 has interlocking elements 14 permanently connected to a tape 16, and elements 15 permanently secured to a tape 17, as best shown in Figures 3 and 4.

The tape 16 is connected by two rows of stitching 18 and 19 to the edge portion 20 of the garment body 10. In addition, a spaced row of hooks 21 is secured to the tape 16, as shown in Figures 2 and 4. The hooks 21 are connected by rivets 22, metal plates 33, and stitching 23. The strain on the hooks 21 is distributed through the seams 18 and 19 to the garment body 10.

On the opposite side of the opening 11 away from the tape 16, is the opposite tape 17 which carries the interlocking slide-fastener elements 15. The tape 17 is secured to the edge portion 24 of the garment 10 by spaced lines of stitching 25 and 26.

Underlapping the slide-fastener tape 17 is a fabric strip 27 which is covered by a fabric shield 28. The fabric strip 27 and the covering shield 28 are connected together at the outer edge, or free edge, by stitching 29 and at the inner end

by the seam 26. By means of the seam 26 the fabric strip 27 and the covering shield 28 are connected to the slide-fastener tape 17 and to the edge portion 24 of the garment. Eyes 30 are secured by rivets 31 and metal plates 33 to the fabric strip 27.

As shown in Figure 6, the slide-fastener elements 14 and the hooks 21 are spaced apart from each other. As shown in Figure 7, the slide-fastener elements 15 are in considerably spaced-apart relation from the eyes 30. The eye-bearing fabric 27 and the covering shield 28 are made sufficiently pliable in crosswise direction to permit the hooks and eyes and the metallic portions of the slide-fastener elements to be drawn while in non-superposed relation against a substantially plane surface when under stress of wearing conditions.

When the slide-fastener elements 14 and 15 are in operative engagement they function freely due to the non-superposed and spaced-apart relation between the slide-fastener and the hooks and eyes. As shown in Figures 1 and 8, the strain will be substantially equally divided between the slide-fastener 12 and the hook and eye fasteners 13. The slide-fastener tapes are made of strong textile fabric and are non-stretchable in direction lengthwise of the linear opening 11. The tapes 16 and 17 are independent of reinforcement by the strips 27 and 28. The tapes 16 and 17 and the plies 27 and 28 provide a junction at the opening which is of minimum thickness and only a small fraction of the thickness of the closure disclosed in my said prior patent, whereby both flexibility and strength are obtained.

When the slide-fastener elements 14 and 15 interlock, the hooks and eyes are first engaged and the slide 35 is then moved upwardly as indicated in the position shown in Figure 1.

It will be noted from Figures 2 and 3 that the lower portion of the eye-bearing fabric strip 27 and the covering shield 28 carrying the duplex set of fasteners are wider than the upper portion thereof so as to underlap all of the fastening elements and thereby prevent any injury to the person using garments having the duplex set of fasteners. Also, the structure disclosed results in a neat fitting construction and one which will be comfortable notwithstanding any peculiar posture of the wearer. When removing the foundation garment from the person, the slide 35 is slid down to the position shown in Figure 2. This downward sliding disengages the slide fastener elements 14 and 15. The hooks and eyes are then disengaged in the usual manner and the garment may then be pulled downwardly over the hips and off the person.

As shown in Figures 1 and 2, I have provided a line of reinforcing stitching 32 which is positioned at the lower end of the elongated opening 11 and obliquely to the opening. The line of stitching 32 does not pass through both tapes 16 and 17 of the slide-fastener 12, but passes solely through the slide-fastener tape 16 and through the eye-bearing strip 27 and covering shield 28.

It is to be noted that an advantage of having the eyes non-yieldably positioned on the eye-bearing fabric is that the user will positively find the eye in a definitely fixed position at all times. This makes for greater ease and quickness of fastening and unfastening. This is entirely different from the eyes shown in my former patent, which were yieldably attached merely by stitching and were movable in all directions after the garment had been worn but a short time.

It is also to be noted that the advantage derived from securing the hooks directly to one of the slide fastener tapes is to cause the hooks to be carried by a strip of single ply thickness and to render the garment at the opening relatively thin and flexible, permitting ease of body movements of the wearer.

In the usual practice, the opening 11 extends from the upper edge downwardly past the waist line. In the type of foundation garment shown in Figures 1 and 2 wherein a frail fabric such as net or lace 36 is employed along the upper portion of the garment, the upper edge of the slide-fastener extends upwardly from the lower edge of the opening and terminates substantially at the lower level of the frail fabric.

The eye-bearing strip 27 and the covering shield 28 are made of relatively flexible layers of fabric and form a thin one-piece flap 37. The flap is a one-piece strip of fabric, that is, continuous in lengthwise direction. The threads of the fabric strip 27 are positioned crosswise of the linear opening 11. The flap 37 is non-stretchable in a direction crosswise of the linear opening, and substantially equally divides the strain with the slide-fastener 12. This arrangement is particularly desirable in foundation garments having panels that are elastic around the waistline to permit the garment to snugly embrace the wearer's body in different positions and wherein the closure means is placed under tension in use. This arrangement of duplex closure means also serves to materially lessen the strain on the slide-fastener and causes it to easily slide and operate freely.

In order to further clarify the workings of this improved closure means, reference is made to Figures 3 and 4, wherein the edge 40 of the metallic portions of the slide-fastener elements 14 will, in assembled relation, be spaced away from the eyes 30 and substantially follow a dot-and-dash line 41, spaced from the eyes 30, as shown in Figure 3.

It is to be noted that while the zipper tape will overlie a portion of the hook elements, the fact that this woven fabric tape is very thin, it will not affect the thickness of the closure. The difficulty that I have found in my prior garment closure was that the metallic portions of the slide-fastener were in full superposed relation with the metallic hooks and eyes.

This expedient of placing the metallic portions of the slide-fastener elements and the metallic hooks and eyes in spaced-apart relation so that they could lie against a substantially plane surface formed by the eye-bearing fabric strip 27, has made it possible to materially reduce the thickness of the connecting portions of the garment at the opening, so that, instead of pressing or pinching into the flesh of the wearer, the garment closure described herewith eliminates this defect.

It is also to be noted that the spaced relation of the eyes 30 from the slide-fastener elements 15 is also clearly brought out by the numeral 42, identifying a lead line terminating in an arrow in Figure 7.

As shown in service position in Figure 8, the two sets of fastening devices, when in use, lie in non-superposed relation against a substantially plane surface; that is, both lie against the substantially flat eye-bearing fabric strip 27 and occupy a minimum of space in a direction crosswise of the length of the garment.

It is to be noted that the woven zipper tapes in use in the art are very thin in comparison with

the interlocking zipper elements at the lengthwise edges of the tapes, which are made of metal and are at least four times as thick as the said tapes. It is obvious that, while one of the zipper tapes overlies a portion of the hooks and eyes, that, due to the thinness of the zipper tape, this overlying of the tape itself does not affect the thickness of the closure to any appreciable extent. It is the four times thicker metallic elements of the zipper which it is very necessary to prevent from overlying the hooks and eyes.

In accordance with the patent statutes, I have described and illustrated the preferred embodiment of my invention, but it will be understood that various changes and modifications can be made therein without departing from the spirit of the invention as defined by the appended claims.

I claim:

1. In a foundation garment having a brassière portion made of frail fabric and having a linear opening extending from the uppermost edge of said brassière portion to an intermediate portion of said garment and being defined by continuous fabric tapes secured to the side edges of said opening, said tapes carrying complementary slide-fastener elements extending upwardly and terminating substantially at the lower level of said frail fabric, a continuous strip of eye-bearing fabric secured to said garment along one side edge of said opening and underneath one of said tapes, each of said eyes being secured directly to said strip and lying fully exposed on said strip when the fasteners are detached, hooks secured directly to one of said slide-fastener tapes, said eyes being positioned in spaced-apart relation from the slide fastener elements secured to the side edge of the garment to which said strip is secured, said spacing being sufficient to permit the metallic portion of the complementary slide-fastener elements to enter between said eyes and slide fastener elements and lie in non-superposed relation with said eyes, said hooks lying fully exposed on said tape when said fasteners are detached, said hooks and eyes extending along the entire length of said opening, the lower portion of the strip carrying said eyes being wider than the upper portion of said strip and being designed to overlap and shield the wearer from contact with said fastener elements when said opening is closed, said hooks and eyes at the upper portion of said garment being spaced closer together than at said lower portion and being independently adapted to absorb the stress in the upper portion of said garment, a row of reinforcing stitching at the lower end of said opening, said garment being elastic crosswise of said closure and causing said slide-fastener elements and said hooks and eyes to be under tension in use, said eye-bearing strip being non-stretchable in a direction crosswise of said linear opening and substantially equally dividing the strain with said slide-fastener, said slide-fastener comprising thin woven tapes and interlocking elements made of metal considerably thicker than said tapes, said spaced-apart relation of said eyes causing said hooks and eyes and said metallic fastener elements to lie in non-superposed relation against a substantially plane surface, thereby causing said garment at said opening to be of minimum thickness and flexible.
2. In a foundation garment having a linear opening extending from the uppermost edge to an intermediate portion of said garment and being defined by continuous fabric tapes secured to the side edges of said opening, said tapes carrying

complemental slide-fastener elements extending upwardly and terminating at an upper level, a continuous strip of eye-bearing fabric secured to said garment along one side edge of said opening, each of said eyes being secured directly to said strip and lying fully exposed on said strip when the fasteners are detached, hooks secured directly to one of said slide-fastener tapes, said eyes being positioned in spaced-apart relation from the slide fastener elements secured to the side edge of the garment to which said strip is secured, said spacing being sufficient to permit the metallic portion of the supplemental slide-fastener elements to enter between said eyes and said slide fastener elements and lie in non-superposed relation with said eyes, said hooks lying fully exposed on said tape when said fasteners are detached, said hooks and eyes extending along the entire length of said opening, the lower portion of the strip carrying said eyes being wider than the upper portion of said strip and being designed to overlap and shield the wearer from contact with said fastener elements when said opening is closed, the hooks and eyes at the up-

per portion of said garment being spaced closer together than at said lower portion and being independently adapted to absorb the stress in the upper portion of said garment, a row of reinforcing stitching at the lower end of said opening, said garment being elastic crosswise of said closure and causing said slide-fastener and said hooks and eyes to be under tension in use, said eye-bearing strip being non-stretchable in a direction crosswise of said linear opening and substantially equally dividing the strain with said slide-fastener, said slide-fastener comprising thin woven tapes and interlocking elements made of metal considerably thicker than said tapes, said spaced-apart relation of said metallic eyes from said metallic slide fastener elements causing said metallic hooks and metallic eyes and said metallic fastener elements to lie in non-superposed relation against a substantially plane surface assumed by said eye-bearing fabric when in use, thereby causing said garment at said opening to be of minimum thickness and flexible.

ABE MEYER BUTOW.
